Inventor:
JAMES W. STUBBS,

James W. Stubbs,

D. Anthony Usina
his Attorney.

UNITED STATES PATENT OFFICE.

JAMES W. STUBBS, OF STEUBENVILLE, OHIO.

BAR-PILING APPARATUS.

Application filed November 3, 1923. Serial No. 672,684.

To all whom it may concern:

Be it known that I, JAMES W. STUBBS, a citizen of the United States, and resident of Steubenville, in the county of Jefferson and State of Ohio, have invented certain new and useful Improvements in Bar-Piling Apparatus, of which the following is a specification.

This invention relates to a bar repiler, and more particularly to a repiler for resetting overturned piles of sheet bar and the like, and has for its object the provision of a single device which may be passed around the overturned pile of bars, connected to a crane or other lifting mechanism, and will automatically right the pile of bars as the device is lifted by the lifting mechanism.

Wherever sheet bars are handled in loose drafts it is almost impossible to avoid upsetting some of them occasionally, either on the cooling beds or in transferring them from one location to another. Heretofore in repiling or resetting the upset bars, the usual method has been to pass a chain around each end of the pile and connect the chains to a crane, which in turn would raise the pile and bump it against a car, the building columns, or any handy object, until the pile was straightened out. This practice consumes from ten to thirty minutes in time, requires several men, is dangerous, and does considerable damage to property.

The present apparatus provides means for automatically repiling or resetting an upset pile of bars in from two to three minutes, with a minimum of labor, and without the necessity of bumping the bars against other objects, thus eliminating the major portion of the labor, the danger, and damage of the old practice.

In the drawings, Figure 1 is an end elevation of an upset pile of bars with the repiling device of this invention in position to lift and reset the pile, as clearly shown in dotted lines in the same figure.

Figure 2 is a side and Figure 3 is an end elevation of a lifting yoke constructed in accordance with this invention.

Referring more particularly to the drawings, the letter A designates the integral bar lifting yoke as a whole, which is substantially U-shaped and composed of a bottom portion 2, and arms or legs 3 and 4, respectively. The leg 3 has its upper or free end terminating in an eye 5, while the leg 4

has its upper or free end terminating in a hook 6.

A lifting chain 7 has one end secured in the eye 5 on the leg 3 and its other end secured to ring 8. A second chain 9 has one end secured to the ring 8 and its other end terminating in an enlarged attaching link 10 adapted to be detachably secured to the hook 6.

The ring 8 is adapted to be engaged with a crane hook 11 suspended from the hoisting chain 12 or other lifting mechanism.

In the drawings, the letter B designates the bars operated upon by the bar yoke, which bars are supported on rails 14 or the like.

During the operation of the device the bar yoke A is kept well greased to facilitate the movement of the bars within the yoke.

To repile the upset or fallen bars B, one or more of the yokes A are placed around the pile by leg or arm 4 under the pile, while the leg 3 passes over the pile. The chain 9 then is secured to the hook 6 on the leg 4 and the whole device lifted by the crane, and due to the novel shape and the greased surface the bars will fall or slide into proper position. After the bars have been righted, it is only necessary for the crane to again lower them onto the supporting rails 14, when the device may be disengaged from the crane hook 11 and the chain 9 disengaged from the hook 6, thus permitting the yoke A to fall down between the supporting rails and be removed.

It will be understood that while I have shown and described the leg 3 as terminating in an eye 5, it may terminate in a hook, if desired, the same as the leg 4. Also it will be understood that two or more of the yokes A may be used to right one pile if desired or necessary, and that many other modifications may be made without departing from the scope of my invention as defined in the appended claims.

I claim:—

1. A bar repiling device comprising the combination with a lifting mechanism, of at least one U-shaped bar yoke adapted to have one of its legs passed under the bars to be piled, and lifting chains attached to the free ends of each of the legs of said bar yoke and to said lifting mechanism.

2. A bar repiling device comprising the combination with a lifting mechanism, of at

least one integrally formed U-shaped bar yoke adapted to have one of its legs passed under the bars to be piled, and lifting chains attached to the free ends of each of the legs of said bar yoke and to said lifting mechanism.

3. A bar repiling device comprising the combination with a lifting mechanism, of at least one integrally formed U-shaped bar yoke adapted to have one of its legs passed under the bars to be piled, a lifting chain secured to an eye formed on the free end

of one of the legs of said bar yoke, a second lifting chain having one end secured to the free end of said first mentioned chain and 15 its other end adapted to be detachably engaged with a hook formed on the free end of the other leg of said bar yoke, and said chains being connected to said lifting mechanism at their junction point, substantially 20 as shown and described.

In testimony whereof I have hereunto set my hand.

JAMES W. STUBBS.
